UNITED STATES PATENT OFFICE.

JULIUS PAULY, OF LOS ANGELES, CALIFORNIA.

EXTENSION FOR FIRE-ESCAPES.

1,140,708.

Specification of Letters Patent. Patented May 25, 1915.

Application filed March 1, 1915. Serial No. 11,377.

To all whom it may concern:

Be it known that I, JULIUS PAULY, a citizen of the United States of America, residing at Los Angeles, county of Los Angeles, State of California, have invented a certain new and useful Extension for Fire-Escapes; and I do hereby declare the following to be a full, clear, and exact description of the invention, such as will enable others skilled in the art to which it appertains to make and use the same.

This invention relates to improvements in extensions for fire escapes, and it may be said to consist in the provision of the novel and advantageous features and in the novel and improved construction, arrangement, and combination of parts as will be apparent from the description and claims which follow hereinafter.

One object of the invention is to provide a novel and improved construction whereby the improvements can easily be applied to existing or standard fire escapes at a comparatively small expense and with little or no modification of said fire escapes.

Another object of the invention is to provide a novel and improved construction in which the stairs are provided with pivotally mounted hand-rails and is pivotally linked to bars which are movably mounted on substantially vertical guideways, and in which the upper end of the stairs is connected with a counterweight, and the upper ends of the stairs and hand-rails have parts thereon co-acting with guides on said bars.

Further objects of the invention are to provide a novel and improved construction of the nature specified, which is simple and economical to manufacture and install, practical and serviceable, attractive in appearance, occupies a comparatively small space, and is well out of the way when not in use, and which is strong, rigid, convenient, safe and effective in use.

Other objects and the advantages of the invention will be apparent to those skilled in the art from a careful consideration of the following description of the preferred form of the construction embodying the invention, taken in connection with the accompanying drawings in which—

Figure 1 is a broken sectional view of a building with a fire escape having the improvements applied thereto; Fig. 2 is a front elevational view of the fire escape, showing the extension stairs in lowered posi-

tion; Fig. 3 is an enlarged broken sectional view taken on the line 3—3 of Fig. 2; Fig. 4 is an enlarged sectional view of the bars and of the sheaves mounted on the cross-piece between the bars, taken on the line 4—4 of Fig. 1; Fig. 5 is a broken elevational view of the bars, crosspiece, sheaves, and of the cable; Fig. 6 is an enlarged broken and partly sectional view taken on the line 6—6 of Fig. 1; Fig. 7 is an enlarged broken sectional view taken on the line 7—7 of Fig. 1; Fig. 8 is an enlarged broken sectional view taken on the line 8—8 of Fig. 1; Fig. 9 is an enlarged broken side elevational view showing the mounting of the counterweight and cable; Fig. 10 is an enlarged broken sectional view showing the stairs latched on one of the guideways; and Fig. 11 is an enlarged broken sectional view taken on the line 11—11 of Fig. 6.

The standard form of fire escape shown in the drawings consists of balconies 12 mounted on the outer wall 13 of the building 14 and arranged near the windows 13' or other openings provided in the second and higher stories of the building. The balconies may be suitably secured to the wall of the building and mounted on brace bars 15 which are suitably secured to the balconies and to the wall of the building, and they may consist of suitable floors or platforms 15' having thereon parapets 16. Suitable stairs 17 may lead in the usual way from an opening in each upper balcony to the next lower balcony.

The improvements which can readily be applied to the standard fire escape will now be described. At one side of the lowermost or second story balcony 12 are arranged the substantially vertical guideways 18, preferably consisting of channel bars, which may be secured in position by angle bars 19 which latter may be riveted or bolted to the guideways and to the lower balconies 12. A crossbar 20 is suitably secured to the upper part of the guideways 18, and a brace-bar 21 may be suitably secured to the cross-bar 20 and to the wall 13. Vertically movable bars 22 are movably mounted on the guideways 18 and preferably consist of angle bars provided with rollers 23 suitably mounted thereon and fitted in the guideways 18. The stairs 24 consist of the side pieces 25, the steps 26 suitably secured between the side pieces 25, and the hand rails 27 which are pivotally linked to the side

pieces 25. The side pieces 25 are connected to the lower portion of the bars 22 by links 28 which latter have one end thereof pivoted on the bars 22 and have the other end 5 thereof pivoted on the side pieces 25 intermediate of the ends of said side pieces. The links 29 preferably have one end portion thereof offset and pivotally connected to the side pieces 25, and have the other end portion thereof pivotally connected to the hand rails 27; one of the links 29 on each of the hand rails being fastened to or integral with that one of the links 28 which is adjacent thereto. The upper end portions of the side 10 pieces 25 have thereon projections or rollers 30 which are fitted in the guideways 31 which are provided on the bars 22, and the upper end portions of the hand rails 27 are provided with preferably hinged projections 15 or rollers 32 fitted in said guideways 31. The counterweight 33 is preferably provided with grooves 34 into which extend the vertical guides 34 and 35 which may be suitably secured in position to the wall 18 20 and the adjacent guideway 18. A cable 36 is suitably connected to the counterweight 33 and to the stairs 24; said cable preferably passing over sheaves 37 mounted on the cross-bar 20, and having branches 38 connected to eyes 39 at the sides of the top portion of the stairs 24. The branches 38 may also contact with sheaves 40 mounted at the 25 ends of the cross-bar 41 at the top of the bars 22, whereby said branches are out of the way of persons using the stairs 24 in going to or from the lowermost balcony 12 30 which preferably has its parapet 16 cut away between the guideways 18. A latch or catch 42 may be provided on the stairs 24 and adapted to coact with a projection 43 on one of the guideways 18 or other stationary part to hold the stairs 24 in raised position. Stops 44 preferably consisting of 35 pieces of angle iron are provided at the lower ends of the guideways 18.

It will be understood that the counterbalanced extension stairs 24 may easily be moved to lowered position to extend between the lower balcony 12 and the ground; 40 by first disengaging the catch 42 from the stationary projection 43, then moving the stairs 24 and vertical bars 22 downwardly to have the lower rollers 23 on the bars 22 engage the stops 44. In moving the stairs 45 24 downwardly the links 28 and 29 act to move the lower portion of the stairs 24 and hand rails 27 away from the bars 22, and, the upper ends of the stairs and hand rails having projections freely fitted in the guideways 31, the stairs and hand rails are caused to extend at a convenient inclination from the lower balcony to the ground, and said links 28 and 29 hold the stairs and hand rails rigidly in proper position for safe use. It 50 will be understood that the counterbalanced

extension stairs 24 may be easily moved to the raised position by first moving or lifting the counterbalanced stairs to move the projections 30 and 32 upwardly in the guideways 31 and have the links 28 and 29 act 70 to move the lower portions of the stairs and handrails thereon toward the bars 22 until the stairs and handrails are substantially vertical, whereupon the links 28 pick up the bars 22 and both the counterbalanced stairs 75 and bars 22 may be easily raised completely out of the way above the ground, and the stairs may then be latched to the stationary projection 43. It will be seen that when the extension stairs are lowered in position, the 80 links 28 and 29 act to move the hand rails 27 away from the stairs to the proper position for use, and when the stairs are raised to vertical position the handrails are moved toward the stairs so that the stairs and 85 hand-rails lie close together and thus occupy a small space.

From the foregoing the construction and its advantageous features will be apparent to those skilled in the art, and it will be seen 90 that the construction is well adapted to accomplish the objects of the invention.

The construction which has been particularly illustrated and described admits of minor changes and modifications—wherefore the right is reserved to all such changes and modifications as do not depart from the spirit and scope of the invention which is defined in the appended claims.

I claim:

1. A fire escape including a balcony, substantially vertical bars movably mounted adjacent to the balcony and provided with guideways, counterbalanced stairs provided with hand rails, projecting parts on the upper end portions of the stairs and hand rails fitted freely in said guideways, and links pivotally connected to said bars and to the stairs and hand rails, said links causing the stairs and hand rails to swing away from said bars when the stairs are lowered in position, and causing the stairs and hand rails to swing toward said bars when the stairs are raised in position.

2. A fire escape including balconies, substantially vertical guideways arranged adjacent thereto, substantially vertical bars movably mounted on the guideways, counterbalanced stairs provided with hand rails, guideways on the bars, projecting parts on the stairs and on the hand rails fitted freely in the last mentioned guideways, and links pivotally connected to the lower end portions of the bars and to the stairs and hand rails, said links causing the stairs and the hand rails to swing away from the bars when the stairs are lowered in position, and causing the stairs and the hand rails to swing toward said bars when the stairs are raised in position.

3. A fire escape including a balcony, substantially vertical guideways arranged adjacent thereto, substantially vertical bars movably mounted on the guideways, a cross bar at the upper end of said vertical bars, sheaves mounted at the ends of the cross bar, a counterweight, stairs provided with hand rails, guideways on said vertical bars, projecting parts on the stairs and on the hand rails fitted freely in the last mentioned guideways, a cable connected to the counterweight and having branches in contact with said sheaves and connected to the top of said stairs at the sides of the stairs, and links pivotally connected to the lower end portions of the vertical bars and to the stairs and hand rails, said links causing the stairs and the hand rails to swing away from the vertical bars when the stairs are lowered in position, and causing the stairs and the hand rails to swing toward said vertical bars when the stairs are raised in position.
4. A fire escape including a balcony, substantially vertical guideways arranged adjacent thereto, stops at the lower ends of said guideways, substantially vertical bars provided with rollers fitted in the guideways and adapted to engage said stops to limit the downward movement of said vertical bars, counter-balanced stairs, hand rails, links having one end portion thereof offset and pivoted on the stairs and having the other end portion thereof pivoted on the hand rails, guideways on said vertical bars, projecting parts on the upper ends of the stairs and the hand rails fitted freely in the last mentioned guideways, and links pivotally connected to said vertical bars and to the stairs and hand rails, and causing the stairs and the hand rails to swing away from the vertical bars when the stairs are lowered in

position and causing the stairs and the hand rails to swing toward said vertical bars when the stairs are raised in position.

5. A fire escape including a balcony, substantially vertical guideways arranged adjacent thereto, stops at the lower ends of said guideways, substantially vertical bars provided with rollers fitted in said guideways and adapted to engage said stops to limit the downward movement of said vertical bars, a cross bar at the upper end of said vertical bars, sheaves mounted at the ends of said cross bar, a counterweight, stairs, handrails, links having one end portion thereof offset and pivoted on the stairs and having the other end portion thereof pivoted on the hand rails, guideways on said vertical bars, projecting parts on the upper ends of the stairs and the hand rails fitted freely in the last mentioned guideways, a cable connected to the counterweight and having branches in contact with said sheaves and connected to the top of said stairs at the sides of the stairs, and links pivotally connected to the lower end portions of said vertical bars and to the stairs and hand rails, and causing the stairs and the hand rails to swing away from said vertical bars when the stairs are lowered in position and causing the stairs and the hand rails to swing toward said vertical bars when the stairs are raised in position.

In testimony whereof, I have signed my name to the specification in the presence of two subscribing witnesses at Los Angeles, county of Los Angeles, State of California, this 20th day of February A. D. 1915.

JULIUS PAULY.
